E. J. STALDER ET AL

GASOLINE RESERVE VALVE

Filed Oct. 8, 1921

Fig. 1.

Fig. 2.

UNITED STATES PATENT OFFICE.

EDWARD J. STALDER AND EDWARD SCHOLZ, OF CHICAGO, ILLINOIS.

GASOLINE RESERVE VALVE.

Application filed October 8, 1921. Serial No. 506,450.

To all whom it may concern:

Be it known that we, EDWARD J. STALDER and EDWARD SCHOLZ, citizens of the United States, residing at Chicago, in the county of Cook and State of Illinois, have jointly invented certain new and useful Improvements in Gasoline Reserve Valves, of which the following is a description.

Our invention relates to improvements in gasoline reserve valves, and more particularly to a valve used in connection with either gravity feed or vacuum feed systems, whereby the flow of gasoline between the supply tank and the carburetor is shut off when the gasoline has reached a predetermined level in the tank, there remaining a reserve quantity of gasoline in the tank, said valve having means whereby the flow may be continued to thence use up the reserve supply. When the supply has been cut off, it indicates to the operator that only the reserve supply of gasoline remains, whereupon the valve may be actuated so as to make use of it to enable him to reach a point where he can receive a fresh supply.

The invention has among its objects the production of a device of the kind described which is simple, convenient, compact, durable, reliable, efficient and satisfactory for use wherever found applicable.

To this end our invention consists in the novel construction, arrangement and combination of parts herein shown and described and more particularly pointed out in the claims.

In the drawings, wherein like reference characters indicate like or corresponding parts,

Fig. 1 is a sectional view of a tank showing our device in place in elevation;

Fig. 2 is a sectional view taken substantially on the line 2—2 of Fig. 1;

Fig. 3 is a sectional view taken substantially on the line 3—3 of Fig. 1;

Fig. 4 is a sectional view taken substantially on the line 4—4 of Fig. 2;

Fig. 5 is a sectional view taken substantially on the line 5—5 of Fig. 2; and

Fig. 6 is a devotional detail of a fragmentary portion of the valve.

In the drawings, wherein we have illustrated the preferred embodiment of our invention, 1 indicates the fuel supply tank, said tank being of any desired shape and ma-

terial, located as desired. The fuel 3 in said tank is fed to the carburetor (not shown) through the valve V, said tank having an outlet 2 formed therein as at the top as shown, and preferably internally threaded to receive the valve V. In the modification shown, the outlet 2 is made up of a pipe portion with a flanged base which is secured to the tank by any suitable means, as by welding, riveting or the like.

One of the valve members comprises a cylindrical threaded portion 5 and an enlarged head portion 6, said head portion forming an annular shoulder 7 at its junction with the portion 5. An annular groove 8 is formed in the member adjacent the shoulder 7 and communicates with a lateral duct 9 which extends longitudinally thereof from the bottom end of the member and terminating at said annular groove, the bottom or inner end of said member having an enlarged, outwardly tapered conical seat 12 to cooperate with the valve member 14 to be hereinafter described.

Surrounding the annular groove 8, but spaced radially therefrom, is a collar or sleeve portion 10 which fits between the shoulder 7 and the end of the pipe 2 and aids in centering the valve. The collar 10 is provided with a laterally offset externally threaded portion having a bore 8' therethrough communicating with the annular groove 8. An outlet or discharge pipe 11 leading to the carburetor, and having an annularly enlarged end 11' may be detachably secured in registry with the bore 8', by any suitable or preferred means, as by a nut 10' whereby the fluid drawn through the duct 9 enters the annular groove 8 and is discharged through the pipe 11.

C coaxial with the conical seat 12 and extending axially through said valve member from one end to the other there is provided a bore 13. Fitting within the bore 13 and projecting beyond the outer end thereof, is a stem 17 threaded at its upper end as at 21 and the lower inner end thereof enlarged and conically tapered to form a conical valve adapted to enter the conical valve seat 12 and bear thereupon. A pair of ducts 15 and 16 are provided longitudinally of the conical valve portion 14 and spaced circumferentially thereon, said ducts being adapted to register alternately with the duct

9 when the valve part 14 is rotated to the proper position, one of the ducts 15 or 16 being out of registry with the duct 9 whenever the other duct is in registry therewith.

5 As shown, extension pipes 19 and 20 are arranged at the ducts 15 and 16 respectively, one of said pipes, as for instance, the pipe 19, being of lesser length than the pipe 20, so that when the duct 15 is in communication 10 with the duct 9, the liquid from the tank will be withdrawn until said liquid falls to the level indicated at 4. Then, in order to drain the remaining liquid from the tank, the valve member 14 is partially rotated so 15 as to place the pipe 20 in communication with the duct 9.

At the upper end of the stem 17 is arranged a cap or nut 23 having an enlarged axial opening 24 therein adapted to receive a spring 25, said spring tending to move or urge the valve member 14 against the valve seat 12 and to compensate for wear and prevent leakage therebetween. A washer 26 may be inserted between the lower end of 25 the spring and the top face of the valve part 6, if so desired. A lock nut 22 or the like may be threadedly secured to the end of the stem beyond the nut 23 so as to prevent the accidental displacement of the nut 30 23 and to protect the threads on the end of the stem.

On the upper face of the annularly enlarged portion 6 there are provided a pair 35 of detents 27-27 which are adapted to receive a ball 29 pressed by a spring 30, said spring fitting into a recess 28 in the member 23. In this manner the operating positions of the valve are determined by the ball, which is yieldably depressed into said 40 detents. The enlarged portion 6 has an indicating mark 31 for example, and arrow, provided thereon, which is adapted to operate with a pair of marks 32 and 33 on the rotatable member 23, so that the operator may quickly determine which of the duct 15 or 16 are in registry with the duct 9.

Assuming that the duct 16 is closed at its 45 upper end against the valve seat 12, and the duct 15 is in registry with the duct 9, then the gasoline in the tank 1 will be withdrawn through the duct 9 until it reaches the predetermined level 4, dependent upon the length of the pipe 19, whereupon the feed through the duct 15 will cease. This indicates to the operator that the reserve supply 50 has been reached, and he being warned, turns the member 23 until the ball 29 falls into the proper detent 27 and the arrow 31 is in registry with the mark 33. This movement of the valve 14 opens the duct 16 into registry with the duct 9, so that the reserve quantity of gasoline may flow through the ducts 16 and 9 to the carburetor, enabling the operator to reach a point where additional fuel may be purchased or secured.

In case it is desired to use the valve for a gravity feed system, the valve would be placed at the bottom of the tank so that the ducts 19 and 20 would extend upwardly thereinto. Then the longer duct, i. e. the 70 one projecting further into the tank would conduct the liquid until the reserve level was reached, whereupon the valve would be operated to throw the shorter duct into registry with the opening 9 to permit the reserve supply in the tank to be drained.

75 It will be noted that any predetermined proportion of gasoline may be considered as a reserve supply, this reserve supply being the difference between the quantities corresponding to the difference in level between the ends of the inlets to the two ducts. The connection with the tank and pipe line may be varied as required, depending upon the particular installation.

80 Having thus described our invention, it is obvious that various immaterial modifications may be made in the same without departing from the spirit of our invention; hence we do not wish to be understood as 85 limiting ourselves to the exact form, construction, arrangement and combination of parts herein shown and described, or uses mentioned.

85 What we claim as new and desire to secure by Letters Patent is:

1. In combination with a liquid supply tank having a discharge opening with an outlet pipe projecting therefrom, a reserve valve comprising a member adapted to be 100 stationarily arranged at said outlet pipe and having a single discharge duct therethrough, a collar on said member coaxial with said outlet pipe and annularly abutting thereagainst, said collar provided with an 105 outlet pipe extending therethrough and communicating with the single discharge duct in said member, a second member movably arranged relative to said first-mentioned member and having a pair of ducts 110 therethrough communicating with the liquid in the tank at different levels, and means for selectively moving said second-mentioned member to place one of said pair of ducts into registry with the single duct of said 115 first-mentioned member and closing the passage through the other of said pair of ducts.

2. In combination with a liquid supply tank, a reserve valve comprising a member 120 adapted to be stationarily arranged at an opening in said tank, said member having an annular groove therein, a duct leading from one end of said member and terminating at said annular groove, a tapered valve seat at said end of the member, a tapered 125 valve member rotatably movable in said valve seat and extending through said first-mentioned member and provided with a pair of spaced ducts therein, adapted to alternately register with the duct through said 130

first-mentioned member and means for partially rotating said valve to selectively position either of said pair of ducts into registry with the duct through said first-mentioned member.

3. In a device of the kind described and in combination, a reserve valve comprising a member adapted to be arranged at an opening in a cooperating supply member and provided with an annular groove and a duct laterally of said groove and extending from the inner end of said valve member and terminating at said groove, said valve member being axially bored, said bore 15 enlarged at its inner end to form a tapered valve seat, a cooperatively tapered valve member arranged to fit said valve seat and to control said duct, said valve having a 20 pair of circumferentially spaced ducts longitudinally therethrough communicating with the liquid in said cooperating supply member at different levels and adapted to alternately register with the duct in said first-mentioned valve member, said second-25 mentioned tapered valve member provided with a stem portion arranged in said axial bore of the first-mentioned valve member and projecting therebeyond, and means for partially rotating said tapered valve to 30 selectively position either of said pair of ducts into registry with the duct in said first-mentioned valve member, and means for yieldably retaining said tapered valve in either of its operating positions.

35 4. In a device of the kind described and in combination, a reserve valve comprising a member adapted to be arranged at an opening in a cooperating supply member, said valve member provided with an annular groove therein, and a lateral duct leading from one end thereof and terminating in said groove, a collar encircling said member over said grooved portion and having an outlet therethrough laterally of and communicating with said annular groove, said collar adapted to annularly abut the opening in said cooperating supply member, said valve member also provided with a bore axially therethrough, taperingly enlarged at 40 its inner end to form an annular beveled valve seat thereat, a cooperatively beveled valve member seating on said valve seat and having a stem extending through said axial bore and projecting therebeyond, said second valve member provided with a pair of 45 longitudinal ducts therethrough circumferentially spaced to alternately register with the duct through said first-mentioned

valve member, the ducts in said second valve member communicating with the liquid in 60 said cooperating supply member at different levels, means for rotatably operating said second-mentioned valve member, means for yieldably holding said operating means at either of its operating positions, and means 65 for constantly resiliently urging said second valve member toward its seat to compensate for wear and prevent leakage therebetween.

5. In a device of the kind described and in combination, a cylindrical valve member provided with an enlarged annular flange at one end and threaded so as to be adapted to engage an opening in a cooperating supply member, said valve member provided with an axial bore taperingly enlarged at one end to form a valve seat, an annular groove adjacent said annular flange, and a longitudinal duct parallel to said bore, opening onto said valve seat and terminating at said annular groove, a collar arranged over said annular groove and spaced from the bottom thereof, said collar annularly abutting said annular flange and adapted to annularly 80 abut said opening in said cooperating supply member, and provided with an outlet laterally thereof and communicating with said annular groove, a valve member having an enlarged head tapered to cooperate 85 with said valve seat and having a stem portion within said axial bore and projecting beyond said first-mentioned valve member, said enlarged head provided with a pair of circumferentially spaced, longitudinal ducts 90 adapted to project into said cooperating supply member to different heights, a nut at the end of said stem whereby the enlarged head may be partially rotated to selectively position either of the ducts therein in registry with said duct through said first-mentioned valve member, a spring within said 95 nut and encircling said stem to constantly pull said enlarged tapered head against its tapered valve seat, and a spring-pressed detent means for yieldably holding said operating nut at either of its operating positions.

In testimony whereof, we have hereunto signed our names in the presence of two subscribing witnesses.

EDWARD J. STALDER.
EDWARD SCHOLZ.
